(57) **CLAIM**

The ornamental design for a set of wheel and spoke assemblies, as shown and described.

DESCRIPTION

FIG. 1 is a front, top, right perspective view of a set of wheel and spoke assemblies comprising a front wheel and a back wheel, showing the new design;

FIG. 2 is a rear, bottom, left perspective view of the set;

FIG. 3 is a right side elevation view of the front wheel;

FIG. 4 is a left side elevation view of the front wheel;

FIG. 5 is a front elevation view of the front wheel;

FIG. 6 is a rear elevation view of the front wheel;

FIG. 7 is a right side elevation view of the rear wheel;

FIG. 8 is a left side elevation view of the rear wheel;

FIG. 9 is a front elevation view of the rear wheel;

FIG. 10 is a rear elevation view of the rear wheel;

FIG. 11 is a right side elevation view of the front wheel with the environmental structure removed;

FIG. 12 is a left side elevation view of the front wheel with the environmental structure removed;

FIG. 13 is a right side elevation view of the rear wheel with the environmental structure removed; and

FIG. 14 is a left side elevation view of the rear wheel with the environmental structure removed.

The broken lines of even length depict portions of the set of wheel and spoke assemblies that form no part of the claimed design.
